CARTRIDGE CASE BASKET

Charles W. Cochran and Adalbert J. Lampert, Aldan, Pa., assignors to the United States of America as represented by the Secretary of the Army

Application November 25, 1953, Serial No. 394,522

9 Claims. (Cl. 220—19)

This invention is a crate for holding a number of manufactured articles which are to be processed.

An object of the invention is to provide a crate which will hold the articles at a predetermined and uniform height.

Another object of the invention is to provide a crate which will hold cylindrical articles of varying lengths with their outer ends at a uniform height.

Another object of the invention is to provide a crate having pedestals for holding cylindrical closed-end articles in an inverted position above the side walls for ease of loading and unloading.

A further object of the invention is to provide a crate having a retaining grille, slideable in guides, from a clamping position locking the articles to their respective pedestals to a released position in which the retaining grille is slid from the clamping position and dropped to rest on the crate body to give unobstructed access to the pedestals while loading and unloading.

Other objects and advantages will be apparent from the following detailed description and the accompanying drawings, in which:

Figure 1 is a top plan of a crate constructed according to the invention and showing the retaining grille in open position.

Figure 2 is a vertical sectional view taken on the line 2—2 of Figure 1, showing the retaining grille in clamping position, and by broken lines in released position.

Figure 3 is an end view of the crate as viewed from the right hand side of Figure 2, and

Figure 4 is a schematic view of the crate in use.

Referring now to the drawings, wherein for the purpose of illustration is shown one form of the invention, the reference character 5 indicates generally a fabricated wire receptacle. The receptacle preferably is made of heavy wire strands of any suitable configuration which will provide the necessary strength and rigidity secured together by welding or other suitable means. One side wall 6 is formed with upright end posts 7 and 8 connected by cross braces 9, Figure 2. A top rail 10 joins the end posts and the cross braces. An opposite side wall 11 is formed with upright end posts 12 and 13 connected by cross braces 14, Figure 4, similar to the braces 9 in the side wall 6. A top rail 15 joins the end posts 12 and 13 and the cross braces 14. The end posts 8 and 13 are continued upwardly and are bent downwardly and toward each other, Figure 3, to form lifting loops 16 and 17 respectively.

Referring more particularly to Figure 3, the end wall 18 is formed with a lower rail 19 and inclined end posts 20 and 21 secured at their lower ends to the respective ends of rail 19 and terminating at their upper ends in a horizontal rail 22 shown as lying in the horizontal plane of top rails 10 and 15 of their respective side walls 6 and 11. The upper ends of the lifting loops 16 and 17 are secured to the respective junctions of the horizontal rail 22 with inclined posts 20 and 21, as clearly shown upon Figure 3, to thus form loops by which the entire crate

2

may be supported and conveyed during processing of the articles loaded therewithin.

An opposite end wall 23 is constructed similarly to the end wall 18 and has a lower rail 24 and an upper horizontal rail 25 joined by inclined end posts 26 and 27. Duplicate drag bars 28 and 29, Figures 1 and 2, are generally U-shaped rods or wires each secured at one end to a respective corner or end post 7 and 12 and at its other end to horizontal rail 25 between the ends thereof. These bars are reinforced by straight lengths of rod 28a and 29a each of which has one end secured to the inside bend of its drag bar and extends outwardly and downwardly with its other end secured to a respective end post between the ends thereof. The purpose of these drag bars is explained in the description of operation of the invention.

The bottom of the crate is formed as an open mesh or grill by spaced parallel longitudinal rods 31 secured at their ends to the respective lower rails 19 and 24, and by spaced parallel transverse rods 32 secured at their ends to the outermost ones of the rods 31. Each rod 32 is connected to each rod 31 at the points where it passes over and in contact therewith. In the model illustrated provision is made for the reception of fifteen articles and the spacing of the bottom rods is regular as clearly shown upon Figure 1. A pedestal 33 is secured to and supported by the rods 31 and 32 at each of the fifteen points where these rods cross. Each pedestal is a fabricated structure formed by securing upright strands of wire to the bottom grill. The lower ends of two wire strands 34, 30 of each pedestal, are secured to a transverse rod at equal distances on opposite sides of a longitudinal rod 31. A third wire strand 35 is secured at its lower end to a longitudinal rod 31 of the bottom closure. See Figure 1. The wires of each group are parallel and extend upwardly in equiangular relation a predetermined distance above the plane of the top rails 10 and 15 of the side walls. Secured to and about the upper outwardly-bent ends of each group of strands 34 and 35 is a reinforcing and spacing ring 36. A second reinforcing ring 37 is secured to and within the strands 34 and 35 intermediate their length. See Figure 2. By this construction each group of the aforesaid upright strands is rigidly united in equiangularly spaced relation to form an article-supporting pedestal.

45 A retaining grille 38, having longitudinal side members 39 and transverse members 40, is positioned above the receptacle 5 and slidably secured thereon. Secured to the top rails 10 and 15 at required intervals are inverted U-shaped guides 41. See Figure 3. The retaining grille 50 is first positioned with its side rails 39 resting upon top rails 10 and 15, respectively and with its end member 40 about midway between the final two rows of pedestals, as shown at Figure 1. The guides 41 are then welded to secure their ends to opposite sides of the respective top rails to thereby secure the retaining grille from detachment from the crate while at the same time permitting the retaining grille to be moved vertically and longitudinally. Cam members 43 equal in number to the number of guides 41, are rigidly secured to the members 55 39 at each corner thereof. From Figure 2 it will be noted that these cam members consist simply in a piece of wire or rod bent near one end and having both ends secured to the underlying member 39. The retaining grille is so constructed and arranged that in the loading position each 60 rod 40 lies about midway between rows of pedestals, as shown at Figure 1 in solid lines and at Figure 2 in dotted lines. When shifted longitudinally to the operating position shown in solid lines upon Figure 2, each rod 40 lies directly above its corresponding row of pedestals. This 65 figure also shows in dotted lines, two shell casings C each in position over a pedestal; and it will be noted that when the retaining grille is first raised to the full extent 70

permitted by guides 41 and then slid horizontally to the left as viewed on Figure 2, the cover is cammed downwardly by coaction between the cam members 43 and the bight portions of guides 41 so that each rod 40 of the retaining grille extends across, engages and firmly holds a row of articles upon the pedestals.

In operation, with retaining grille in the position shown upon Figure 1, the crate is loaded by inverting a shell casing or like article downwardly over each pedestal as indicated in dotted lines, Figure 2. The retaining grille is then raised and forced to the left until all casings are held firmly upon the pedestals.

The method of processing articles of manufacture is illustrated in Figure 4, wherein a loaded crate 5 is shown being carried through such processes as washing, pickling, annealing, heat treating, phosphatizing and the like. A tank 45 used in the above mentioned processes is provided with a rub rail 46 in the bottom thereof. Suitably secured above the tank is a trolley 47 which forms a track 48 for roller carriages 49. Secured to each carriage is a cable or the like 50 to which a pair of hooks 51 are attached, only the near one being visible in the drawing. The hooks 51 engage the lifting loops 16 and 17 and support the crate during its travel through the bath, the top level of which is indicated by the letter B. When a loaded crate is lowered into the bath, air or other gases are trapped inside the articles under treatment, such as cartridge cases, and in order to treat all surfaces of the cases to the bath it is necessary to tilt the crate sufficiently to allow the entrapped gases to escape through the open end of the processed article. When the crate is moved in the direction indicated by the arrow A, the drag bars 28 and 29 come into contact with the rub rail 46. Continued movement of the carriage 49 tilts the crate to the second position shown in Figure 4 wherein the open ends of the cases are now uppermost so that the air previously entrapped can escape and the entire inner surface of casings are subjected to the processing bath.

In the claims the term "upwardly" is to be interpreted with respect to the positions of the parts as shown upon Figures 2 and 3.

It is to be understood that the form of the invention, herewith shown and described is to be taken as a preferred example of the same, and that various changes in the shape, size and arrangement of parts may be resorted to, without departing from the spirit of the invention or the scope of the subjoined claims.

Having now fully disclosed the invention, what we claim and desire to secure by Letters Patent is:

1. A rectangular fabricated wire crate comprising end and side walls, a bottom closure secured thereto, a plurality of spaced pedestals secured to said bottom closure each pedestal serving to internally support the closed end of an article to be processed at a uniform height from said bottom closure, a plurality of guide members secured to the upper edge of said side walls, a retaining grille slideable in said guides from released to clamping positions, cam means on said retaining grille cooperable with said guide members for depressing said retaining grille into contact with the articles to hold them firmly on their respective pedestals when said retaining grille is slid to clamping position.

2. A rectangular receptacle for holding articles of manufacture to be processed comprising end and side walls, a bottom closure secured thereto, each of said side walls having a top rail, a plurality of outwardly extending guide members secured to said top rails, a retaining grille having side rails confined within said guide members for limited sliding movement from a released to a clamping position, a plurality of pedestals secured to said bottom closure and extending outwardly beyond said top rails supporting said articles of manufacture beyond said side walls for ease of loading and unloading, and cam means on said retaining grille cooperating with said guide members to cam said retaining grille against the outward end

of said articles of manufacture when said retaining grille is in closed position.

3. A fabricated wire crate comprising spaced side walls, spaced end walls connected at their ends to said walls, a bottom closure secured to said side and end walls to form a receptacle, a plurality of spaced pedestals secured to said bottom closure each pedestal formed to support a closed end cylinder, an inverted U-shaped guide secured to the top of each side wall adjacent the ends thereof, a fabricated retainer having side members longitudinally slideable in said guides a predetermined distance, and cam means slideable with said retainer to engage the closed end of said inverted U-shaped guide to cam said retainer into close contact with the closed end of each cylinder to hold each said cylinder securely to its pedestal when said retainer is in clamping position.

4. A rectangular fabricated wire crate comprising end and side walls, a fabricated wire bottom closure secured thereto, a plurality of spaced fabricated wire pedestals secured to said bottom closure each pedestal shaped to conform to the internal contour of a closed-end article to be processed, a plurality of inverted U-shaped guide members secured to the upper edge of and extending above said side walls, a fabricated wire retaining grille having side rails slideable between the legs of said U-shaped guide members from released to clamping positions, and wedge shaped cam members on said side rails slideable between said guide legs and contacting the closed end of said U-shaped guide for camming said retaining grille into close contact with said closed-end article when said retaining grille is slid into clamping position.

5. A rectangular fabricated wire crate comprising end and side walls, a bottom closure secured thereto, a plurality of spaced pedestals secured to said bottom closure each pedestal supporting an article to be processed at a uniform predetermined distance above the top of said walls, a plurality of inverted U-shaped guide members secured to the upper edge of and extending above the top of said side walls, a fabricated wire retaining grille having side rails slideable between the legs of said U-shaped guide member from released to clamping positions, and cam members on said side rails slideable between said guide legs and contacting the closed upper end of said U-shaped guide for camming said retaining grille into contact with each of said articles to be processed said retaining grille dropping to rest on the top of the side walls when slid to released position.

6. In an open wire crate, a bottom comprising a first plurality of spaced parallel rods and a second plurality of spaced parallel rods secured over and in contacting right angular relation with said first plurality of rods to form a grill, and a pedestal secured to and upstanding from said bottom, said pedestal comprising a pair of upstanding wires each having its lower end secured to one of said second plurality of rods on opposite sides of its intersection with the contiguous one of said first plurality of rods, and a third upstanding wire having its lower end secured to said contiguous one of said first plurality of rods, and ring means interconnecting the top ends of said wires in equi-angularly-spaced relation.

7. In an openwork crate for the processing of tubular articles, first and second rods bent into closed rectangular form, four rods connecting the corresponding corners of said first and second rods to hold the same in parallel spaced relation and define a top and a bottom respectively, a first plurality of rods secured at their ends to opposed sides of said bottom in spaced parallel relation, a second plurality of rods secured at their ends to the remaining opposed sides of said bottom in spaced parallel relation and over and in contact with said first plurality of rods to define therewith a plurality of regularly-spaced points of intersection, and a pedestal riding from each said point of intersection, each said pedestal comprising three upstanding wires in equiangularly-spaced relation, two of said wires having one end of each secured to one of said sec-

ond plurality of rods and the third having its end secured to the contiguous one of said first plurality of rods, and a ring connecting the upper ends of the wires of each pedestal to receive a tubular article to be processed.

8. An openwork crate as recited in claim 7, and a retaining grille for said crate, said retaining grille comprising a plurality of rods fixed in spaced parallel coplanar relation, each said rod passing over an aligned row of pedestals when said retaining grille is fixed to said crate in operating position thereover.

9. An openwork crate as recited in claim 8, the tops of said pedestals extending above the plane of the top of said crate, a plurality of U-shaped loops secured to and upstanding from each of two opposed sides of said top and cam members secured to the corresponding sides of said retaining grille, each said cam member cooperating with the bight portion of a corresponding loop to cam said

5
